UNITED STATES PATENT OFFICE.

OTTO A. HOKANSON, OF WOODSTOCK, ILLINOIS, ASSIGNOR TO WOODSTOCK TYPEWRITER COMPANY, OF WOODSTOCK, ILLINOIS, A CORPORATION OF ILLINOIS.

LINE-LOCK.

1,307,051.

Specification of Letters Patent. Patented June 17, 1919.

Application filed June 3, 1918. Serial No. 237,933.

To all whom it may concern:

Be it known that I, OTTO A. HOKANSON, a citizen of the United States, residing at Woodstock, in the county of McHenry and 5 State of Illinois, have invented certain new and useful Improvements in Line-Locks, of which the following is a specification.

This invention relates to typewriters, and more particularly to the line lock mechanism 10 thereof and the means for releasing it when desired.

The principal object of the invention is to provide a new and improved construction of this kind which is automatically operated 15 to lock both the key levers and the space bar against actuation, and is manually released by the depression of a key lever.

The invention consists in the novel construction, combination and arrangement of 20 the several parts.

In the accompanying drawings—

Figure 1 is a fragmentary view of certain parts of a typewriter illustrating the application of a line lock and release mechanism 25 to the parts thereof with which it co-operates.

Fig. 2 is a plan view partly in section of a portion of the line locking mechanism;

Fig. 3 is a detail view showing portions of the line lock mechanism in a different 30 position; and Fig. 4 is a fragmentary detail view showing the release of the line lock.

In a typewriter it is desirable to provide means for automatically preventing the actuation both of the key levers and of the 35 space bar near the end of the writing line, and this is accomplished by providing the movable carriage with means for engaging certain mechanism which is moved to engage the key levers and space bar in their normal 40 positions to prevent them from being actuated so that the typewriter mechanism and the carriage cannot be moved another letter space. It is also just desirable to provide means for manually releasing the line locking 45 mechanism to write an additional character if desired. The present invention contemplates the provision of improved mechanism for accomplishing both of these results.

A plurality of key levers 1 are pivoted at 50 their rear ends in a sub-frame 2, which is mounted in a typewriter frame 3. A space bar 4 is pivotally mounted on a transversely extending shaft 5, and an arm 6 secured to the shaft has an angular extremity adapted 55 to engage one end of a spacing lever 7, the

other end of which is connected to a universal bar frame 8, or to other suitable mechanism for actuating the escapement mechanism, which is not shown in the present case. The key levers actuate pivoted type bars 60 upon their downward movement in a well-known manner.

Extending transversely under the key levers 1 is a rail 9 which is pivotally mounted in brackets 10 at the sides of the typewriter frame to swing upon pivot screws 11. The rail 9 is adapted to be moved into engagement with an angular notch 12 formed in the forward edge of a downwardly extending portion 13 of each of the 70 key levers 1. Secured to the rail is a bracket 14 to which one end of a link 15 is pivoted, the other end being formed with a slot 16 slidable upon a headed pin 17 secured to the arm 6. The upper edge of this link, adjacent 75 the slotted portion 16, is formed with an abutment 18 which is adapted to co-operate with an adjustable stop screw 19 secured to the sub-frame 2.

In order to move the rail 9 one of the 80 pivoting brackets 10 is provided with a headed pin or rivet 20 which is adapted to be engaged in an angular slot in a link 21, the slot having a portion 22 in which the pin 20 is normally engaged, and an angular portion 23 85 with an enlargement 24 at the end thereof through which the head of the pin 20 may be passed in assembling or taking the machine apart. At its forward end this link 21 extends below the shaft 5, and the extremity 25 90 thereof is loosely engaged on its under side by the bent end 26 of a pivoted key lever 28 which is operable from the front of the typewriter. Attached to the adjacent ends of this link and to a bent end 27 of the lever 28 are 95 springs 29 and 30 which tend to draw the link forwardly and to hold this end of the lever in its downward position. The other end of the link 21 is attached to a bell crank 31 at the rear of the typewriter frame 3, and another link 32 is connected at one end of the 100 bell crank and at the other end to a lever 33 mounted at the top of the frame. This lever carries an engageable pin 34 which is located in the path of a pivoted stop arm 35 105 carried by a margin stop 36 which is adjustable on a bar 37 which moves with the carriage transversely of the typewriter frame in the well-known manner. It will be seen that the tendency of the spring 29 110

at the lower end of the link 21 is to hold the lever 33 so that its projecting pin 34 is in the uppermost position where it will be engaged by the pivoted member 35 on the 5 transverse movement of the bar 37.

In operation the rail 9 is normally in the full line position, shown in Fig. 3, and at this time the key levers 1 and the space bar 4 can be freely depressed for letter writing 10 and spacing movement in the well-known manner, the abutment 18 of the link 15 being in position so that it will not engage the stop 19 when the space bar is depressed. In this condition the pin 20 will be in the 15 portion 22 of the slot in link 21, and the link will be drawn forward by its spring 29. As soon as the projection 34 of the lever 33 is engaged by the member 35, the lever will be rocked on its pivot drawing the links 32 20 and 21 upwardly, and this action will cause the movement of the rail 9 into the notches 12 of the key levers 1, and will cause the link 15 connected to the rail 9 to be moved into a position where its abutment 18 will 25 engage the stop 19, as shown in Fig. 1. This will prevent the depression of either of the key levers or the space bar 4, and no further action is possible in the letter spacing direction until the key lever 28 is 30 depressed. When the inner end of this lever 28 is raised, the forward end of link 21 is also raised until the pin 20 is at the angular portion of the slot in the link, whereupon it is free to fall by its own weight out 35 of engagement with the notches 12, because the pin 20 will at this time move freely in the forward portion 23 of the slot, and this will cause the link 15 to be moved clear of the stop 19 so that the key levers 1 and the 40 space bar 4 can be depressed at will. When the finger is taken from the forward end of the key lever 28, and after the carriage and member 35 pass over projection 34 of lever 33, spring 29 draws the forward end 45 of the link 21 downwardly and forwardly, and this movement causes the slot 23 to ride up on the pin 20 until the portion 22 is reached, whereupon the pin 20 will be reengaged with this portion of the angular slot, the rail 9 at this time being maintained 50 in its forward position so that the link 21 and the rail 9 are again connected in their normal relation ready for another line-locking operation.

55 I claim:

1. In a line lock, a plurality of pivoted key levers each having a substantially vertical portion intermediate the ends with aligned notches in the front edges of the vertical portions, a transverse rail pivoted below the key levers with a rear edge engageable in the notches, a movable link having a pin and slot connection with the rail, a spring tending to draw the link and rail forwardly, and means for raising the link when

the rail engages the notches so that the rail will fall out of engagement with the levers.

2. In a typewriter, the combination with a plurality of key levers and a space bar including a rearwardly extending actuating 70 arm, of a line lock comprising a rail extending below the levers and means for pivotally mounting it to swing into engagement therewith, a link pivotally connected to the rail having a sliding engagement with the said arm, and a stop to engage the said link when the rail is in engagement with the key levers.

3. In a line lock, the combination with a plurality of key levers, of a rail extending 80 transversely below the levers and mounted for swinging movement into engagement with the levers, means for moving the rail comprising a link with an angular slot, and a pin carried with the rail for engagement 85 in the said slot, the link being movable so that the pin will allow the rail to fall by its own weight out of engagement with the key levers.

4. In a line lock, the combination with a 90 plurality of key levers, of a rail extending transversely thereof and mounted for swinging movement into and out of engagement with the levers to prevent their depression, means for moving the rail positively 95 into engaging position, said means comprising a pin, a link with an angular slot in which the pin is movable, an actuating connection attached to one end of the link, a key lever for raising the other end of the 100 link to allow the rail to fall by its own weight out of engagement with the key levers, and means for returning the link to its normal position after it has been raised by the key lever.

5. In a line lock, a plurality of key levers, a rail swingingly mounted to engage the key levers to prevent their depression, means for positively moving the rail in one direction comprising a pin and a link with 110 an angular slot one portion of which is normally engaged by the pin, means for raising the link so that the pin will ride in the other portion of the angular slot due to the weight of the rail to release the key levers from engagement therewith, and a spring acting upon the link to return the pin to the normal portion of the slot by moving the link with respect to the rail.

6. In a line lock, the combination with a 120 plurality of pivoted key levers, of a transversely extending shaft, a space bar connected to the shaft, an arm mounted on the shaft and extending rearwardly therefrom, a transversely extending rail, brackets for pivotally mounting the rail, a link pivoted to the rail having a sliding pin and slot connection with the said arm, an adjustable fixed stop to engage the link when the rail 125 engages the key levers, means for positively 130

moving the rail and the link into engaging position, said means comprising a pin projecting from one of the brackets, a link with an angular slot for engaging said pin and a connection at one end of the link to move it positively in one direction, and releasing means comprising a key lever engaging the other end of the link and resilient means acting upon the adjacent ends of the releasing lever and the said link.

7. In a line lock, a plurality of key levers, of a transversely extending rail, brackets for pivotally mounting the rail for swinging movement, a link having an angular slot, a pin in connection with one of the brackets and slidable in the slot, a connection at one end of the link for moving it positively in one direction, a spring at the other end of the link for drawing it in the other direction when the said connection is

released, and means for raising the spring end of the link to allow the pin to slide from one portion of the angular slot into the other portion thereof due to the weight of the rail, the said spring returning the pin to the first-mentioned portion of the slot when the said connection at the other end of the link is released.

8. In a typewriter, the combination with a plurality of pivoted key levers and a pivoted space bar, of a line lock comprising a rail to swing into engagement with the levers, and a slidable lock in connection with the line lock to prevent the operation of the space bar when the rail is in engagement with the key levers.

In testimony whereof I have signed my name to this specification on this 31st day of May A. D. 1918.

OTTO A. HOKANSON.
